UNITED STATES PATENT OFFICE.

FREDERICK WILLIAM KOEHLER, OF WILKINSBURG, PENNSYLVANIA, ASSIGNOR TO AMERICAN ATMOS CORPORATION, OF WILKINSBURG STATION, PITTSBURGH, PENNSYLVANIA, A CORPORATION OF NEW YORK.

REGENERATOR FOR BREATHING APPARATUS.

1,309,896.

Specification of Letters Patent.

Patented July 15, 1919.

Application filed March 27, 1919. Serial No. 285,700.

To all whom it may concern:

Be it known that I, FREDERICK WILLIAM KOEHLER, a citizen of the United States, and a resident of Wilkinsburg, in the county of 5 Allegheny and State of Pennsylvania, have invented certain new and useful Improvements in Regenerators for Breathing Apparatus; and I do hereby declare the following to be a full, clear, and exact description 10 of the invention, such as will enable others skilled in the art to which it appertains to make and use the same, reference being had to the accompanying drawings, and to letters or figures of reference marked thereon, 15 which form a part of this specification.

My invention relates to regenerators for breathing and resuscitating devices, and has for its object the construction of a simple retainer for the regenerating substance, 20 usually a hydrate of sodium or potassium, and is designed for the convenient and rapid filling of such generators with the regenerating substance and to facilitate complete absorption.

It also embodies a construction which is simple to manufacture, readily taken apart, and readily reassembled, and includes a container or can having an inlet opening for respiration air and an outlet opening for purified air, to which openings the usual conduits are connectible.

Referring to the drawings, in which like parts are similarly designated—

Figure 1 is a perspective view, partly broken away to show the interior of a two-compartment regenerator.

Fig. 2 is a plan view, partly in section, of the air distributor designed to retain the regenerating substances.

Fig. 3 is a perspective view of one of the end grids of the distributor.

Fig. 4 is a section showing one of the reticulated or net air-passage tubes.

Fig. 5 is a section on line 5—5 of Fig. 1, 45 showing the method of holding the partitions separating the distributor.

Fig. 6 is a horizontal plan view, with the cover removed, of a single compartment regenerator.

50 The regenerator shown in Fig. 1 comprises a metallic casing or can 1 divided by a removable partition 2. This partition fits closely against one end of a can by means of

a resilient flange 3, and at the other end of the can by means of resilient flanged lugs 4, 55 formed by cutting away a portion of the partition between said lugs at 5, the cut-away portion between the lugs forming an air passage from one compartment, 6, to the other compartment, 7.

60 Each compartment is provided with a conduit connection, such as 8 and 9, respectively. The partition 2 is held in place by spaced lugs 10 on the top and bottom of the can 1, preferably, but not necessarily, made by indenting the metal at the top and bottom so as to form a recess 11 into which the edge 65 of the partition seats and is securely held, when the can is closed by the lid 12.

70 In each compartment is placed a distributing unit such as shown in Fig. 2. Such a unit comprises a pair of end-grids 13, more clearly shown in Fig. 3 in perspective, of sheet metal, having turned-up flanges 14, preferably unsoldered or unconnected at their corners, so as to make resilient contact with the 75 sides of the compartment in which they are placed. The sheet metal grid has slots 16 formed in it by punching up the metal so as to provide flanges 15 surrounding these 80 slots. The flanges, preferably but not necessarily, have the same direction from the body of the plate as the flanges 14.

85 There is one such grid at each end of a compartment, and these grids are held together to form a unit by reticulated metal or woven wire flat tubes 17, as shown in section in Fig. 4. Such a flat tube is formed by a sheet of wire net, for example, placed over a mandrel with the edges clenched together or interlocked or turned over at the narrow edge of the tube, as shown at 17a.

90 These wire tubes are inserted in the grids, as shown in Figs. 1 and 2, and by reason of the rough or feather-edges on the flanges 95 15 formed by the punching operation, the tubes are firmly held in place and hold the grids together to form a unit, which unit is removable as a whole from the compartment in the can 1.

100 In order to fill such a regenerator can, it is simply necessary to remove the lid 12 and pour the granulated regenerating material over the tubes between the end grids, filling the spaces between the tubes 17. The tubes 105 17 themselves form air passages through

their interior for the air to be purified, and by reason of their reticulated or open structure, enable the air to come into proper contact with the absorbing material between 5 the tubes and to be purified thereby.

The grids are so arranged in their respective compartments that there is formed a chamber at each end thereof, as indicated at 18, between the end walls of the container 10 1 and the respective grids and the tube ends, and in order to more securely hold the elements in position and prevent them from shaking during use, I prefer to round the corners of the container 1, as shown at 19, 15 this rounded portion determining the width of the chambers 18 between the grids and the end walls of the container.

In operation air is admitted through one of the connections shown, for example 8, 20 passes into the chamber 18 at such connection, passes through and around the netting tubes 17 in contact with the purifying substance to the opposite end into a like chamber 18, thence through the cut-away portion 25 5 in the partition 2 in the chamber 18 of the next unit at the front end of the container and out through the connection 9, or vice versa. The compartments 6 and 7 are thus included in series between the conduit 30 connections 8 and 9.

In Fig. 6 I have shown a single compartment regenerator, to all purposes identical with one-half of the regenerator shown in Fig. 1, there being an inlet connection at 35 one end, as 8, and an outlet connection 9 at the other end, the air passing straight through the regenerator.

The most difficult question is the re-charging of such regenerators after the sodium 40 hydrate has become semi-liquid by absorbing carbonic acid. With my improved regenerator this is a simple matter, all that is necessary being to remove the lid 12 of the regenerator when the whole interior can be 45 lifted out, separated and washed in running water, after which it is dried and replaced and refilled, as above described.

As already stated, the flanges 14 of the grids are not connected to one another at 50 the corners of the grid, so that resilient contact is made against the four side walls of each compartment, which ordinarily is sufficient to prevent regenerative material from entering the distributing chambers 18, however, if desired, a strip of packing such as of 55 cotton fabric may be laid along the edge of the grid flanges before the lid is placed on, as an extra precaution.

The absorption of the carbonic acid from 60 the respired air is complete.

I claim—

1. A regenerator for breathing apparatus and the like, comprising a casing and a unit for distributing regenerating material there- 65 in, comprising end grids and parallel reticu-

lated tubular members held in place by said grids, the regenerating material being distributed between the tubular members and grids.

2. A regenerator for breathing apparatus, 70 comprising a casing and a unit therein for retaining regenerating material, comprising flanged end members having openings therein and flat tubular members inserted in the openings in said end members, the regenerating material being filled in the spaces between said tubes and end members.

3. In a regenerator for breathing apparatus; a casing, a removable lid therefor, a removable partition having a cut-away 80 portion at one end and extending from one of the parallel end walls of the casing to the other end wall thereby forming two compartments connected together at one end and a removable regenerator unit in each 85 compartment, the lid and bottom of said casing having spaced lugs between which said removable partition is retained.

4. A regenerator for breathing apparatus, comprising a casing divided by a partition 90 into two compartments, said partition having a cut-away portion at one end to provide communication between said compartments, a conduit connection for each compartment arranged to include the compartments in series between said connections, and a regenerating unit in each compartment comprising a pair of end grids and reticulated, flattened tubes held in the grid openings, said grids spaced from the end 100 walls of the respective chambers to form distributing chambers.

5. A regenerator unit comprising end grids having resilient, peripheral flanges, and the grid openings having flanges, and 105 flat, tubular members of wire net inserted in the grid openings.

6. A regenerator, comprising a casing having rounded corners, a regenerator unit therein having flanged end members, and 110 wire net tubular members inserted in said end members, said end members maintained spaced from the end walls of said casing by the curvature of the corners of the casing to form air distributing chambers.

7. A regenerator, comprising a casing having rounded corners, and spaced lugs on its top and on its bottom, a removable partition held between said lugs and having a cut-away portion, said partition dividing 115 the casing into compartments, a regenerator unit in each compartment comprising grids having peripheral flanges and flanged slots, flattened wire netting tubes held in said slots, said grids being maintained spaced 120 from the ends of said compartments by said rounded corners, and conduit connections including the compartments between them.

8. A regenerator unit comprising a pair of grids having flanges unconnected at their 130

corners and flanged slots, said flanges having roughened or feathered edges, and flattened wire net tubes whose edges are clenched at the narrow sides of the tubes, 5 said tubes being retained in the slots of said grids.

9. A regenerator for breathing apparatus and the like, comprising a casing, and a unit for distributing regenerating material 10 therein, having end grids and reticulated tubular members held in place by said grids, the regenerating material being distributed between the tubular members and grids.

10. A regenerator comprising a casing 15 having rounded corners, a regenerator unit therein having an end member maintained spaced from the end wall of said casing by the corner curvature of the casing to form

a distributing chamber between said member and end wall.

11. A regenerator for breathing apparatus comprising a casing having a removable top and a bottom, a removable partition in the casing having a resilient flange at one end engaging one wall of the latter and resilient 25 lugs at the other end engaging the opposite wall of the casing, thereby forming two compartments communicating through an air passage at one end formed between said lugs, and a removable regenerator unit in 30 each compartment.

In testimony that I claim the foregoing as my invention, I have signed my name hereto.

FREDERICK WILLIAM KOEHLER.
